UNITED STATES PATENT AND TRADEMARK OFFICE
Certificate

Patent No. D. 607,713 S

Patented: January 12, 2010

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Man Ki Yoo, Skokie, IL (US).

Signed and Sealed this Fifteenth Day of March 2011.

ROBERT M. SPEAR
Supervisory Patent Examiner
